(57) **CLAIM**

We claim the ornamental design for a head mounted display, as shown and described.

DESCRIPTION

FIG. 1 is a front perspective view of a head mounted display of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The evenly spaced broken lines represent portions of the head mounted display that form no part of the claimed design. Additionally, the unevenly spaced broken lines in the drawings define the limits of the claimed design.
